UNITED STATES PATENT OFFICE.

JOHN W. WEEKS, OF PROVIDENCE, RHODE ISLAND.

GAS-PRESSURE REGULATOR.

No. 885,681.

Specification of Letters Patent.

Patented April 21, 1908.

Application filed May 15, 1907. Serial No. 373,874.

To all whom it may concern:

Be it known that I, JOHN W. WEEKS, a citizen of the United States, residing at Providence, in the State of Rhode Island, have invented certain new and useful Improvements in Gas-Pressure Regulators, of which the following is a specification.

My invention consists in the improved link connection between the inlet valve and the regulating medium, and in the employment of an automatic valve for preventing the ejection of the quicksilver from its annular holding chamber upon the application of a back pressure in the gas pipes for the purpose of clearing out the foreign matter therefrom.

In the accompanying drawings: Figure 1 represents a vertical section of a gas pressure regulator embodying my improvement. Fig. 2, represents a horizontal section taken in the line 2 2 of Fig. 1.

In the drawing, A is the valve casing, which broadens out as it extends upward into a cylindrical portion B, as shown in Fig. 2. Inside of the cylindrical portion B, is placed the inverted cup formed shell C which is secured tightly to the valve casing A so as to form a narrow annular watertight chamber D, between the periphery of the shell C, and the inner wall of the said cylindrical portion B. The chamber D is partially filled with quicksilver and serves to receive the lower portion of the regulating gasometer E, which fits loosely therein.

The frame F is secured to the bottom of the valve casing A, by means of the screws a, a, and to the end b of the said frame are loosely pivoted a pair of links G, only one of which can be shown in the sectional drawing Fig. 1, the said links being loosely pivoted at opposite sides of the ear c, of the swinging valve H, and between the said links G and the said ear, and at opposite sides of the ear c, are loosely pivoted a pair of links I, only one of which is shown in the drawing. The arms e of the pair of forked links J, only one of which is shown in the drawing, are jointed at k to the links I, the said pair of forked links J, being loosely pivoted at opposite sides of the standard d of the frame F. The arms e' of the said forked links J, are loosely jointed to the opposite sides of the valve spindle K, which spindle is arranged to pass loosely through the opening f in the shell C, and to the upper end of the said valve

spindle is secured the gasometer E, over the top of which are placed the removable adjusting weights L, L, whereby the pressure of the flow of gas from the meter is determined.

The shell C is provided with the openings g, g, through which the gas passes from the chamber M of the valve casing to the chamber N of the gasometer, the said shell C, being also provided with the valve-seat h. The valve O is annular in form and rests loosely upon the circular valve-seat i, formed upon the periphery of the collar P, which is secured to the valve-spindle. The chamber Q, over the gasometer E, is provided with the loose removable cover R.

The operation of the gas regulator may be described as follows: The regulator is preferably inserted into the main supply-pipe of the ordinary gas-supply system between the meter and the burners. The gasometer E rises and falls freely in the annular chamber D, and is sealed by the mercury contained in the said chamber. The gasometer is connected to operate the swinging valve H, through the action of the links G, I and J. Now when all the burners in the system are closed, the gas pressure rises in the pipes and forces up the gasometer, so that the valve H is carried over against its seat S, and the further supply of gas is shut off. And when one of the burners is relighted the gasometer will be caused to fall slightly and open the valve sufficiently to supply the proper quantity of gas to the said burner. And when two burners are lighted the gasometer will fall a little lower and admit a greater quantity, and so on until all of the burners are lighted, when the valve will be opened sufficiently to supply them.

When a back pressure is applied to the gas-supply pipes for the purpose of cleaning them, the valve H will be forced back to its seat, and the valve spindle K is carried upward until the annular valve O is closed at both its upper and lower seats, so that a sudden increase of back pressure within the gasometer and consequent dispersion of the quicksilver in the chamber D will be prevented. By means of the annular construction of the valve O the proper seating of the valve is assured. And by the employment of the forked links J the joint j between the arms e' of the said forked links and the valve spindle K is removed from the joint k be-

tween the arms e' of the said forked links and the links I , whereby a more direct movement is imparted to the valve spindle K .

I claim as my invention:

- 5 1. In a gas regulator, the combination of the valve casing, the inlet valve, the gasometer, the gasometer spindle and the connecting links, whereby the inlet valve and gasometer are caused to move simultaneously, and a 10 connected valve for closing the gas passage to the chamber of the gasometer, upon the closing of the inlet valve.
- 15 2. In a gas regulator, the combination of the valve casing, the regulating gasometer, the cup-formed shell provided with openings through which the gas passes from the chamber of the valve casing to the chamber of the gasometer, the spindle of the gasometer passing loosely through an opening in the said 20 shell, the forked link jointed at one arm to the spindle of the gasometer the frame to which the forked link is pivoted, the link jointed to the other arm of the forked link, and the inlet valve jointed to the said frame, 25 and to the link which is jointed to the arm of the forked link.
3. In a gas regulator, the combination of the valve casing, the inlet valve, the gasome-

ter, the gasometer spindle, the circular valve seat upon the said spindle, the connecting links whereby the inlet valve and gasometer are caused to move simultaneously, the shell which serves to separate the chamber of the gasometer from the chamber of the valve casing and is provided with an opening between the said chambers, the valve seat upon the shell surrounding the said opening, and the loose annular valve held between the said valve seats of the gasometer spindle and the casing.

4. In a gas regulator, the combination of the valve casing, the inlet valve, the gasometer, a gasometer spindle connected therewith, connections from said spindle to said inlet-valve, the shell provided with an opening 40 adapted for communication between the chamber of the valve casing and the chamber of the gasometer, the circular valve seat surrounding the said opening, and a valve carried by said gasometer spindle for closing 45 said opening upon the closing of the inlet valve.

JOHN W. WEEKS.
